UNITED STATES PATENT OFFICE.

JOHN G. KERST, OF SPRINGFIELD, ILLINOIS, ASSIGNOR TO HARRY G. KERST, OF SPRINGFIELD, ILLINOIS.

PLOWING-MACHINE.

1,177,039.

Specification of Letters Patent. Patented Mar. 28, 1916.

Application filed April 10, 1912. Serial No. 689,887.

To all whom it may concern:

Be it known that I, JOHN G. KERST, a citizen of the United States, residing at Springfield, in the county of Sangamon and State 5 of Illinois, have invented new and useful Improvements in Plowing-Machines, of which the following is a specification.

This invention relates to the class of plows and more specifically to that class of plowing machines which comprise a plurality of plow blades and which are commonly called 10 gang plows.

An object of this invention is to provide a gang plow which has disposed thereon a 15 plurality of helical screws which coöperate with the plow blades in the manner set forth hereinafter.

Another object of this invention is to provide a plowing machine which is constructed 20 of but a few parts and one which is durable, easy to control and efficient in operation.

With the above and other objects in view, my invention relates to such details of construction and in the arrangement and combination 25 of the several parts as will be herein-after fully described and specifically pointed out in the appended claims.

In describing my invention in detail reference will be had to the accompanying drawings 30 wherein like characters denote like or corresponding parts throughout the several views and in which,

Figure 1 is a plan view of my invention, the engine and its controlling clutch and 35 lever being removed for clearness. Fig. 2 is a side elevation thereof. Fig. 3 is a plan view of my invention showing the specific means for controlling the engine, in detail. Fig. 4 is a front elevation of my invention. Fig. 5 40 is a detail view. Fig. 6 is a detail sectional view of the mounting casting for the plow beams and drive shafts.

Referring now to the drawings wherein is illustrated the preferred form of my invention, the numeral 1 designates the main frame, which frame is spanned by the cross pieces 2, the said cross pieces being connected by the members 3. A U-shaped frame 7 is connected with the main frame 1 and 45 has mounted thereon brackets 4 through which brackets extend the shaft 5 as is clearly shown. The shaft 5 is supported at each extremity by the traction wheels 6 and has keyed thereon a gear wheel 8, the gear

wheel serving a purpose which will presently appear. 55

Meshing with the gear wheel and near the top thereof is a pinion 9 which is carried upon a shaft 10 which is journaled through the bracket 10' as is clearly shown in Fig. 4. 60 The shaft 10 is connected with the engine 11 (the engine being of any well known type) and is provided intermediate its ends with a friction clutch 12 which is operated through the medium of the arm 13 on the lever 14. 65 The movement of the lever 14 occurs when the lever 15 is rocked upon its pivot 16, the lever 14 being engaged by its bifurcated end 17.

For the purpose of supporting the bracket 70 18 which has journaled thereto the stub shaft 19, the bail 20 is swung upon the under side of the frame 7. The stub shaft 19 is supported intermediate its ends by the bracket 21 which is carried upon the standard 75 22 and is provided at one end with a gear wheel 23 which receives motion from the gear wheel 8. The other end of the stub shaft is supported upon the member 24 by means of the bracket 25 and has thereon a 80 second gear wheel 26 which gives motion to the pinions 27 and 28 journaled respectively on the stub shafts 32 and 31. Struck down portions 29 are provided in the pieces 22 and 24 and are provided with bearings 30 and 85 30' which support the stub shafts 31 and 32 which carry the pinions 27 and 28 respectively.

For a purpose hereinafter appearing, blocks 33 are positioned upon the members 3 90 which blocks have the stub shafts 31 and 32 journaled therethrough, the said stub shafts carrying upon their inner ends bevel gear wheels 34 and 35. The blocks are provided with offset portions 36 which receive one end 95 of the rods 37 which carry the bevel gear wheels 38, the last named beveled gear wheels adapted to mesh with those first mentioned as is clearly shown in Fig. 1. Provided upon the blocks are extensions 39 100 to which are connected the beams 48 which are supported at their rear ends by means of the angle members 49, the said angle members being disposed as clearly shown. The rods 37 being in a plane parallel to the frame 1 are provided intermediate their ends 105 with the screws 42, they performing the function of cutting the sod ahead of the

point of the plow, thus decreasing the work usually performed by that member. Gear wheels 43 are provided on the rear ends of the rods 37, the said gear wheels meshing 5 with other gear wheels 44 as shown, whereby motion is given to the shafts 45 upon which are positioned the helical screws 46. The last couple of spirals of the helical screws are broken or toothed and sharpened 10 as shown at 46' whereby the earth which is upturned by the plow blades 47 is completely pulverized. The screws 46, act as draft means to impart a forward thrust and also serve to draw the earth onto the plow blades and the screws are tapered rearwardly to accommodate the contour of the plow blades and so that the screws can extend substantially the entire length of the blades. Thus the screws can be arranged abreast of 15 20 the plow blade to directly coat therewith. Further, the screws 46 are conned to conform to the shape of the mold boards so as to lie closely adjacent thereto and effectively coat therewith to break up the earth up- 25 turned by the shares. Frames 76—77 and 78—79, fastened to beams 48, at 80—81 and 82, support the shafts 37 and 45.

Supporting the plow blades 47 are the beams 48 which are pivoted at their ends as 30 shown and provided with the arms 49 which have pivotal connection with the links 50, the said links being operated by the levers 51 which carry pawls 52 adapted to operate upon the segmental racks 53. Pivoted han- 35 dles 52' are provided upon the levers 51 which operate the pawls 52 as clearly illus- trated, the plows and screws thereof being lifted together.

The rear end of the lever 15 is provided 40 with the handle 54 and is adapted to be held in different positions through the medium of the rack 55 which is mounted upon the cross piece 56 as shown.

The operator's seat is supported upon the 45 frame work through the medium of the leaf springs 58 and 59. It will now be readily obvious that the operator within his seat can easily control the different levers above mentioned. I find it advantageous to pro- 50 vide some efficient means for guiding the machine in its travel and to this end the rear of the frame is provided with a caster-wheel 60 which has connection with the bi- furcated end 61 of the rod 62 which is in- 55 serted in the sleeve 63 as shown. The sleeve 63 is provided with the extension 64 and is adapted to be secured to the frame work be- 60 neath one end of the leaf spring 59. For more securely supporting the rod 62, the members 65 are provided, which members have connection with the same intermediate its ends and with the under side of the frame as shown at 66. A segmental rack 67 is pro- 65 vided upon the rod 62 which rack meshes with the gear wheel 68 supported by a pin

69 in the block 70 which is supported by the substantially U shaped bracket 71. For the purpose of receiving the sprocket chain 72, pin 69 is provided with a second gear wheel, the other extremity of said sprocket chain being supported by the gear wheel 73 which is carried upon the rod 74 which supports the operating wheel 75. The operating wheel 75 is disposed in front of the operator's seat so that the machine can be guided without the necessity of the operator leaving his post.

It is thought that the operation of the machine will be understood from the foregoing description and a detailed disclosure 80 of the same is thought to be unnecessary.

I desire to be understood that I may make slight changes in the construction and combination of the parts of my machine without departing from the spirit of the invention 85 in the least, provided such changes fall within the scope of the sub-joined claims.

Having thus fully described my invention what I claim as new and desire to secure by Letters Patent is:—

1. In a device of the character described, a structure supported by a plurality of wheels, plow blades hung from the under side of said structure, helical screws abreast of and coating with the plow blades, other screws for breaking the ground in front of each plow blade, and means for propelling said structure for the purpose described.

2. In a device of the character described, a structure supported by a plurality of wheels, plow blades swinging from the under side of said structure, helical screws abreast of and coating with said plow blades and disposed thereabove, means for raising and lowering said plow blades and said helical screws, and other screws operating in front of said plow blades and means for propelling said structure for the purpose de- 105 scribed.

3. In a device of the character described, a structure supported by a plurality of wheels, a plurality of plow blades swung from the under side of said structure, helical screws abreast of and coating with said plow blades, said screws having their edges sharpened, means for raising and lowering said blades, other screws operating in front of said blades and an engine for propelling said vehicle for the purpose described.

4. In a device of the character described, a structure supported by a plurality of wheels, plow blades swingingly connected to the under side of said structure, helical screws disposed above said plow blades, other screws disposed in front of said plow blades, means for propelling said structure and means operated by the travel of said structure adapted to rotate said screws for the purpose described.

5. In a device of the character described,

a structure supported at its forward end by 5 wheels connected by an axle, a caster wheel supporting the rear end of said structure, plow blades hung from the under side of said structure, helical screws operating abreast of and coacting with said plow blades, the winds of said helical screws being tapered toward their rear ends, other screws operating in front of said plow blades, 10 means for propelling said structure and means operated by said axle whereby said screws are rotated for the purpose described.

6. In a device of the character described, 15 a structure supported at its forward end by a plurality of wheels, an axle connecting said wheels, a caster wheel supporting the rear end of said structure, plow blades hung from the under side of said structure, helical screws operating abreast of and coacting with said plow blades, means for raising and lowering said plow blades, means for propelling said structure, means operated by said axle for causing rotary motion of said 25 screws and means for guiding said caster wheel for the purpose described.

7. In a device of the character described, a structure supported at its forward end by a plurality of wheels, an axle connecting said 30 wheels, cross arms spanning said structure, members connecting said cross arms, a caster wheel supporting the rear end of said structure, a plurality of plow blades hung from the under side of said structure, means for raising and lowering said plow blades, helical screws supported abreast of and coacting with said plow blades, the winds of said 35 helical screws being tapered toward their rear ends to conform to the contour of the plow blades, other screws operating in front of said plow blades, means for propelling said structure, means operated by said axle whereby rotary movement may be transmitted to said screws and means for guiding 40 said caster wheel for the purpose described.

8. In a device of the character described, a structure supported at its forward end by a plurality of traction wheels, an axle connecting said traction wheels, a caster wheel 45 supporting the rear end of said structure, a plurality of plow blades swingingly connected with the under side of said structure, means for raising and lowering said plow blades through the medium of the plow 50 beams, helical screws supported abreast of and coacting with said plow blades, the winds of said helical screws being tapered toward their rear ends to conform to the contour of the plow blades, other screws operating 55 in front of said plow blades, means for propelling said structure, mechanism operated by said axle for permitting rotary motion 60 of said structure.

tion to said screws, a rod journaled through said structure, a hand wheel carried upon the upper end of said rod, mechanism connected to the other end of said rod whereby said caster wheel may be moved so as to guide said structure for the purpose described.

9. In a device of the character described, a structure supported at its forward end by a plurality of traction wheels, an axle connecting said traction wheels, a gear wheel carried upon said axle, a plurality of plow blades swingingly connected to the under 75 side of said structure, common means for raising and lowering said plow blades, helical screws operating abreast of and coacting with said plow blades, other screws operating in front of said plow blades, the under 80 side of said last named screws being in the same horizontal plane as the under sides of said plow blades, means for operating said structure, mechanism operated by said gear wheel for permitting rotary motion to said 85 screws, a caster wheel supporting the rear end of said structure, an operator's seat mounted upon said structure and means for guiding said caster wheel for the purpose described.

10. In a device of the character described, a structure supported at its forward end by a pair of wheels, an axle connecting said wheels, a gear wheel carried upon said axle, cross pieces spanning said structure, members extending longitudinally thereby, a 95 caster wheel supporting the rear end of said structure, a plurality of plow blades swingingly connected to the under side of said structure, hand levers for raising and lowering said plow blades, helical screws operating abreast of and coacting with said plow blades, the winds of said screws being tapered toward their rear ends to conform with the contour of said blades, other screws operating in front of said plow blades and in the same horizontal plane, rods supporting 100 said second mentioned screws, gear wheels positioned upon each end of said rods, mechanism connecting said first mentioned 110 gear wheel and the gear wheels on one end of said rods, shafts supporting said helical screws, gear wheels upon one end of said shafts, last mentioned gear wheels adapted to mesh with the gear wheels on the adjacent ends of said rods and means for propelling said structure whereby rotary motion 115 is imparted to said screws for the purpose described.
